WINDOW STRUCTURE

Elmer A. Westman, Fenton, Mich.

Application January 10, 1950, Serial No. 137,773

3 Claims. (Cl. 189—67)

1

This invention relates to improvements in windows and particularly to window assemblies of the awning type.

Awning type window assemblies include a window frame and one or more swinging window sash sections. It is common practice to provide a plurality of vertically superimposed sash sections pivotally supported within the frame for outward swinging movement of the bottom of the section and downward sliding movement of the top of the section. Such sections are commonly coupled together by operating mechanism for movement in unison. Inasmuch as such windows are designed to obtain maximum ventilation they are frequently provided in relatively wide widths.

The sash operating mechanism is designed to be of light weight and of relatively small size so as to function within a limited space and due to flexibility in parts thereof, as for example an operating cross shaft, a sash section may close against the frame on one side but fail to close tightly thereagainst on the opposite side.

An object of this invention is to provide operating mechanism for the swinging sash sections which may be readily adjusted to obtain complete closure of the sections at all points against the window frame.

A further object is to provide such operating mechanism with an adjustment which is completely concealed when the window is closed, which is of simple construction and so designed that accurate adjustment can be readily accomplished.

Another object is to provide operating mechanism with adjustment means whereby that side of a sash section furthest removed from the operator handle may be closed against the window frame ahead of the side of the sash section which is adjacent to the operator handle in order that when the sash section is drawn down against the frame it will close completely at all points thereagainst.

Other objects, advantages and meritorious features will more fully appear from the following description, claims and accompanying drawings, wherein:

Fig. 1 is a perspective of a window structure embodying the invention;

Fig. 2 is a horizontal section taken on the line 2—2 of Fig. 1;

Fig. 3 is a vertical section taken on the line 3—3 of Fig. 1;

Fig. 4 is a vertical section through the window assembly taken on the section line 4—4 of Fig. 2

2

and showing the sash broken away to disclose the operating mechanism;

Fig. 5 is a vertical section through the window assembly taken on a line similar to Fig. 4 but showing the sash sections swung open instead of closed as in Fig. 4;

Fig. 6 is a vertical section taken on the plane of the window broken away to illustrate the operating mechanism;

Fig. 7 is a fragmentary perspective showing a part of the operating mechanism;

Fig. 8 is a horizontal section taken on the same line as Fig. 2 showing the window section before it is completely closed;

Fig. 9 is a fragmentary perspective of one of the fulcrum links; and

Fig. 10 is a sectional view taken on the line 10—10 of Fig. 9.

The window assembly comprises a stationary window frame which is adapted to be fixed within the wall of a building. The window assembly is shown as fabricated out of sheet metal. The window frame comprises a pair of similar side frame members 20 which are channel-shaped in cross-section as shown in Figs. 2 and 8. These side frame members are connected together at the top by a header 22 which is also channel-shaped in cross-section and at the bottom by a sill member 24, which is likewise channel-shaped in cross-section. The channels of these side frame members, header and sill, open outwardly as shown. A removable header weatherstrip portion 26 is provided and shown particularly in Figs. 1, 3, 4 and 5. It seats over an upstanding ledge formed on the header of the frame.

Within the frame there may be mounted a plurality of sash sections, each pivotally supported to be swung outwardly. In the particular embodiment shown, two such sash sections are illustrated. The upper section is indicated by the letter U and the lower section is indicated by the letter L. The two sections are similar and similarly supported for pivotal swinging movement. Each section is shown as comprising a metal sash 30 provided with a pane of glass and this sash is adapted to close over the open channel of the stationary window frame, as shown particularly in Figs. 2 and 3. Each sash section is pivotally supported by a pair of fulcrum links indicated generally as 32 in Figs. 4, 5 and 6.

These links are pivoted to opposite sides of the sash sections as at 34. The opposite ends of the links are pivoted to horizontally opposite points of the side frame members 20 through the employment of stationary brackets 36. These

brackets 36 are fixed to the side frame members as by rivets, brazing or the like. The links are pivoted as at 38 to the brackets as shown generally in Figs. 4 and 5.

Each link is adjustable lengthwise consisting of cooperating end portions 40 and 42 as shown in Figs. 9 and 10 specifically. One end portion 42 is shown as provided with side flanges 44 adapted to slidably receive therebetween the opposite end portion 40. End portion 40 is slotted lengthwise as at 46. A retaining screw 48 is adapted to fasten the two portions together at adjusted positions. The meeting faces of the two portions are provided with grooves adapted to increase the frictional engagement of the flat faces so that they will better retain their linear adjusted positions.

The two sash sections are adapted to be swung outwardly at the bottom and moved vertically downward at the top to adjustable open positions through the use of an operating mechanism which comprises a pair of slidable bars 52 disposed on opposite sides of the window frame within the channel side frame members 20. Retaining plates 54 are secured as by brazing, riveting or the like to the side frame members of the window and overhang the bars as shown in Figs. 5 and 7 particularly. Each sash section is pivoted to each of the bars. Each sash section is provided with a pair of arms 56, one arm secured to each side of the section at the top as by rivets, brazing or the like. The arm projects upwardly and inwardly of the sash section and is pivoted at 58 to a bar 52. It is apparent, therefore, that slidable movement of the bars 52 will swing the sash sections to the open or closed positions.

To actuate the bars slidably vertically, there is provided manual operating mechanism in the form of a hand crank 60 mounted upon the outer end of a worm shaft 62 which shaft is supported within a housing 64 secured to one side frame member 20 as shown in Figs. 4 and 5. An arm 66 is provided with gear teeth 68 which mesh with the worm on the shaft 62 to be actuated thereby. This arm is pivoted at 70 as shown particularly in Figs. 4 and 5. The outer end of the arm is coupled by a link 72 with a link 74 of toggle structure. The link 74 is mounted upon a cross-shaft 76 to rotate therewith, which cross-shaft extends transversely of the bottom of the window frame and is journaled for rotation. The opposite end of link 74 is coupled by the other link 78 of the toggle structure with slidable bar 52. It is coupled therewith upon the pivot 58 which pivots the arm 56 of the sash section to the slidable bar 52 as shown in Figs. 5 and 6.

It is apparent, therefore, that through operation of the worm shaft 62 by the crank 60 the gear arm 66 actuates the toggle links 74 and 78 to move the slidable bar 52 vertically. There is a toggle link 74 mounted at each end of the cross-shaft 76 so actuation of the cross-shaft by the toggle link which is connected directly with the manual operating mechanism swings the toggle at the remote end of the cross-shaft so that the two slidable bars 52 are moved in unison and swinging movement is imparted to both sides of the window. As the slidable bars 52 are drawn downwardly, the upper ends of the swinging sash sections are pulled downwardly and the lower ends are swung outwardly as shown in Fig. 5. Reverse

operation produces closing of the swinging sash sections.

In order that each swinging sash section may close completely all around against the stationary frame, it is necessary that one be able to adjust the fulcrum links 32. For this reason these fulcrum links are so constructed as to permit of lengthwise adjustment as hereinabove described. By adjusting one link relative to the other link, it is possible to insure that opposite sides of the swinging sash section will both be closed tightly against the stationary frame.

It has also been found that there is a certain amount of flexibility in the operating mechanism. For example, there is torsion in the cross-shaft 76. Likewise it has been found desirable to close that side of a swinging sash which is most remote from the manual operator against the window frame before closing that side of the swinging sash which is adjacent to the manual operator against the frame.

If the side which is adjacent to the operator is first closed against the frame, it then becomes very difficult, if not impossible, to pull the remote side tight against the frame. It is, therefore, desirable to so adjust the operating mechanism, as for example, by relative adjustment of the fulcrum links that the side of the sash section which is remote from the operator be brought against the window frame ahead of the opposite side of the sash section. This is shown in Fig. 8, for example, wherein one side of the sash section is shown as already in engagement with the window frame while the opposite side of the sash section is still spaced therefrom.

When the operating mechanism is arranged to produce this result of closing the side of the sash remote from the operator against the frame ahead of the side of the sash adjacent to the operator, it is then possible to continue actuation of the operator to draw the adjacent side down against the frame. There is sufficient give in the entire structure to permit this result. Due to this construction the sash sections may be drawn tightly against the window frame at all points.

What I claim is:

1. A window assembly comprising, in combination, a frame, a plurality of vertically superimposed sash sections swingably supported within the frame, each sash section being swingably supported at opposite ends upon a fulcrum link, each of said fulcrum links pivoted at one end to one side of the sash section and pivoted at the opposite end to the adjacent side of the frame, each of said links consisting of two end portions telescopically articulated for longitudinal adjustment of the length of the link, an operating mechanism including a rotatable shaft extending transversely of the frame at the bottom and having an operator crank coupled with one end of the shaft at one side of the frame to rotate the shaft and having a pair of operating bars coupled with opposite ends of the shaft to be actuated thereby and coupled with the several sash sections to swingably actuate the same in unison, said bars extending along the inside of opposite sides of the frame between the frame and the sash sections, the fulcrum links of each sash section being relatively longitudinally adjustable with respect to each other to position the side of the sash opposite the operator crank in closer proximity to the frame than the other side of

the sash so that in the closing of the sash section the side of the sash section furthest from the operator crank is closed against the frame ahead of that side of the sash section adjacent to the operator crank.

2. A window assembly comprising, in combination, a frame, a sash section swingably supported within the frame, an operating mechanism including a rotatable shaft extending transversely of the frame at the bottom and having an operator crank coupled with one end of the shaft at one side of the frame to rotate the shaft, a pair of operating bars coupled with opposite ends of the shaft to be actuated thereby and coupled with the sash section to swingably actuate the same, said bars extending along the inside of opposite sides of the frame between the frame and the sash section, a pair of fulcrum links swingably supporting the sash within the frame with each link pivotally mounted at opposite ends at fixed positions along the vertical extent of the sides of the sash and frame, and the fulcrum link pivotally mounted on the side of the frame adjacent the operator crank being of a longer length than the link at the other side of the frame thereby permitting the sash during the closing movement to abut the frame at the side opposite the operator crank before abutting the side adjacent the crank.

3. A window assembly comprising, in combination, a frame, a sash section swingably supported within the frame, an operating mechanism including a rotatable shaft extending transversely of the frame at the bottom and having an operator crank coupled with one end of the shaft at one side of the frame to rotate the shaft, a pair of operating bars coupled with opposite ends of the shaft to be actuated thereby and coupled with the sash section to swingably actuate the

same, said bars extending along the inside of opposite sides of the frame between the frame and the sash section, the sash section being swingably supported within the frame upon a pair of linearly adjustable fulcrum links adapted to provide as an axis of rotation for the sash a line meeting the plane of the frame at adjustable oblique angles thereby permitting the side of the sash opposite the operator crank to abut the frame at adjustable intervals before the other side as the sash is closed, and each of said fulcrum links having telescoping end portions pivotally respectively mounted at fixed positions along the vertical extent of the sash and frame.
